UNITED STATES PATENT OFFICE

ERNEST PENBERTHY, OF DETROIT, MICHIGAN, ASSIGNOR TO CHICAGO PNEUMATIC TOOL COMPANY, OF NEW YORK, N. Y., A CORPORATION OF NEW JERSEY

FLUID-PRESSURE TOOL

Application filed January 27, 1925. Serial No. 5,004.

This invention relates to fluid pressure percussion tools of the type used in mining, quarrying and similar operations. In particular it relates to tools of this type especially adapted and intended for use in stopping and still more particularly to tools utilizing a two diameter piston or impact member. The invention is, however, by no means limited to such use but embodies features capable of general application.

Among the objects of the invention are to provide an improved construction and arrangement of control mechanism which will result in a tool characterized by high piston speed and penetrating power, and in general to improve prior construction in the interest of more efficient and satisfactory operation.

With these and other objects in view the invention is illustrated in the accompanying drawings in what is now considered to be its preferred form. In the drawings, Fig. 1 is a longitudinal sectional view of so much of a drill as is necessary to illustrate the invention; and Fig. 2 is a similar view but partly cut away showing the operative parts of the drill in a different position.

The embodiment of the invention chosen for the purpose of illustration comprises a stopping drill having a cylinder 3 to which an air feed cylinder 4 is attached. Within the drill cylinder 3 is mounted for reciprocatory movement a two diameter piston 5 consisting of a head 5^a fitting the large bore 3^a of the piston chamber and with a reduced stem 5^b extending rearwardly therefrom and fitting the small bore 3^b of the piston chamber. The blows of the percussive member or piston 5 are imparted to the drill bit or steel 6 supported in the usual manner in a front head or chuck either directly or through an anvil 8 slidably mounted in a bushing or guide member 9 interposed between the front head 7 and the drill cylinder 3.

The motive fluid for actuating both the air feed and the percussive piston 5 is admitted through the usual throttle valve 10. The motive fluid for the percussive motor enters directly into a chamber 11 which communicates directly with the small bore 3^b of

the piston chamber so that the end of the piston stem 5^b is continuously subjected to the pressure of the live motive fluid and serves as a constant pressure area for urging the piston in a forward direction. The 55

other pressure areas of the piston comprising the front and rear faces of the head 5^a are intermittently supplied with motive fluid under control of an automatically actuated valve 12. This valve is mounted for recip-

rocatory movement in a valve chamber 13. Valve 12 is of the spool type having end heads 12^a and 12^b of equal diameter connected by a reduced neck 12^c. Motive fluid reaches the valve through a passage 14 connecting directly with the chamber 11 and by a second passage 15 which communicates with a groove 15^a in the small bore 3^b of the piston chamber. Thus passage 15 is piston

controlled, motive fluid from chamber 11 having access thereto only when the rear end 60 of the stem 5^b on its forward movement uncovers the groove 15^a. Passages 14 and 15 terminate in grooves 14^a and 15^b adjacent the rear or right hand end or head 12^a of the 65 valve in position to be controlled thereby;

thus when the valve is in its rearward position (Fig. 1) motive fluid from passage 14 passes around the neck of the valve 12^c to a passage 16 terminating in a groove 16^a at 70

the rear of the large bore 3^a of the piston chamber; when the valve moves to its forward position (Fig. 2) connection is broken between the passages 14 and 16 by the head 75

12^a of the valve but established between passage 15 and a passage 17 extending from the rear end of the valve to the front end of the piston bore 3^a to effect the return stroke 80

of the piston. The front head 12^b of the valve controls an exhaust port 18 which is 85

uncovered in the forward position of the valve (Fig. 2) and placed in communication with passage 16 thus serving as an auxiliary 90

exhaust for the rear face of the piston head 5^a, the main exhaust 18 being piston controlled and alternately connected by the latter in its reciprocations with the piston 95

chamber before and behind piston head 5^a. To accomplish the shifting of the valve in timed relation with the movements of the 100

piston the valve head 12^a has two restricted ports 20 and 21 within the limits of the live air groove 14^a in both positions of the valve, the one communicating with an axial bore 5 20^a within the valve extending to the front end of the latter, and the other opening directly into the rear end of the valve which may be hollowed out as indicated at 22 if desired. Both ends of the valve are thus 10 supplied continuously with motive fluid in limited amount, that which enters port 20 and passes through bore 20^a to the front end of the valve being vented to the piston chamber in certain positions of the piston by a 15 vent passage 23 while that which passes through port 21 to the rear end of the valve has access to the piston chamber through the piston return passage 17. This combination of a restricted fluid supply to the ends of 20 the valve vented through the valve chamber together with the piston controlled main exhaust provides for the shifting of the valve at precisely the right instant.

The operation of the drill is as follows:

25 With the parts in the position shown in Fig. 1 motive fluid admitted by the throttle valve 10 to the chamber 11 has access directly to the end of the piston stem 5^b and through passage 14, valve chamber 13 and passage 30 16 to the rear face of piston head 5^a thus driving the latter on its forward or working stroke. The piston return passage 17 communicating with the rear end of the valve is open to exhaust through the piston chamber 3^a and main exhaust 19. As the piston advances the stem 5^b uncovers the groove 15^a admitting motive fluid from chamber 11 to passage 15, the groove 15^b of which remains sealed by valve head 12^a. Soon after the 40 piston head 5^a closes the main exhaust 19 the air in the front of the piston bore 3^a begins to be compressed by the advancing piston and to be forced into passage 17 to build up pressure against valve head 12^a, this pressure being increased by the live motive 45 fluid admitted in limited amount through port 21. Just as the piston delivers its blow, head 5^a passes beyond exhaust port 19 and throws the rearward end of piston bore 3^a open to exhaust (Fig. 2). The pressure heretofore obtaining in vent passage 23 immediately falls and the valve shifts to the position shown in Fig. 2. Immediately the motive fluid heretofore trapped in 55 passage 15 by head 12^a of the valve pours into passage 17 and reaches the front face of piston head 5^a in time to catch the piston as it rebounds and to effect its rearward stroke. At the same valve shifting instant 60 communication between passage 16 and the live air passage 14 is cut off by head 12^a but the auxiliary exhaust port 18 is uncovered by head 12^b. This permits the escape of 65 any air trapped by the piston head 5^a in

the rear end of bore 3^a after it closes main exhaust 19, thus avoiding back pressure and contributing to a full rearward stroke of the piston. The stem 5^b of the piston closes groove 15^a just before the head 5^a of the piston opens the front end of the piston chamber to the main exhaust 19, the rearward movement of the piston then being continued until exhaust 19 is fully opened by the expansion of the motive fluid in the passage 17 augmented by the limited amount of motive fluid entering through port 21. The momentum acquired by the piston carries it against the constant pressure on the end of the stem 5^b well beyond the main exhaust 19 whereupon the closing of the vent passage 23 by piston head 5^a causes the motive fluid admitted by port 20 to build up quickly against the head 12^b of the valve and shift the latter, since the fluid pressure passing across head 12^a from passage 15 is vented to atmosphere through port 19 and offers no substantial resistance to the movement of the valve.

To prevent leakage of motive fluid along the piston stem 5^b between the groove 15^a and the end of bore 3^a when the piston is on its rearward stroke, which leakage would interfere with the full rearward stroke of the piston, a groove 24 is provided to intercept such leakage, this groove having a connection 25 to atmosphere.

I claim as my invention:

1. In combination in a fluid pressure percussive tool having a cylinder with a two diameter bore, a two diameter hammer piston fitting said cylinder bore, said piston having two pressure areas for driving it in one direction and a single pressure area for returning it, one of said first-named areas being continuously subjected to the motive fluid and the two remaining areas being intermittently subjected to the motive fluid, motive fluid supply passages extending to said intermittent areas, one of said passages being controlled by said piston and the other independent of piston control, and a valve controlling both said passages.

2. In a fluid pressure percussive tool, in combination, a reciprocatory piston having two pressure areas for driving it in one direction and a single area for returning it, means subjecting one of said first named areas continuously to motive fluid, and means subjecting the two remaining areas to intermittent pressure comprising passages extending to said areas, the one being independent of said piston and the other under control of said piston, a valve controlling both said passages, said valve also controlling an auxiliary exhaust for one of said areas.

3. In a fluid pressure percussive tool, in combination, a reciprocatory piston having two pressure areas for driving it in one

- direction and a single area for returning it, means subjecting one of said first named areas continuously to motive fluid, and means subjecting the two remaining areas to intermittent pressure comprising passages extending to said areas, the one being independent of said piston and the other under control of said piston, a valve controlling both said passages, and means including 5 connections from said independent supply passage to opposed pressure areas of the valve for effecting shifting of the valve in timed relation with the movements of said piston.
4. In control mechanism for a fluid pressure tool having a two diameter piston with two small pressure areas for driving it forwardly and one large pressure area for returning it, a valve of the spool type having 10 end heads of equal diameter connected by a reduced neck, two live air passages terminating adjacent one valve head, one of said passages being controlled by said piston, means continuously passing motive fluid in limited amount from the other live air passage to the ends of the valve to shift the latter, vent 15 passages extending from both ends of the valve to the piston chamber, the vent from one end serving as the supply passage for 20 the return stroke of the piston, thereby to effect the shifting of the valve in one direction by limited live air augmented by air compressed by the piston and forced into 25 said return passage near the end of its forward stroke, thereupon to admit motive fluid in substantial amount from said piston controlled passage to said return passage to effect 30 the return or non-working stroke of the piston.
5. In control mechanism for fluid pressure percussive tools of the type having a cylinder and a piston reciprocable therein, in combination, a valve having a pressure area for shifting the same, a passage extending 35 from said area to the piston chamber to admit pressure fluid thereto to drive the piston in one direction, a piston controlled passage extending to said valve for connection with said first named passage on shifting of 40 the valve for admitting live air to said first named passage and means continuously admitting live air in limited amount to said area to assist in effecting both the shifting of the valve and the movement of the piston.
6. In valve mechanism for fluid pressure percussive tools of the type having a cylinder and a percussive member reciprocable therein, in combination, a spool valve having 45 end heads of equal diameter and a reduced connecting portion, means continuously passing motive fluid in limited amount to both ends of the valve, means comprising ports and passages under control of one of said 50 heads for directing the motive fluid in alter- 55 nation to opposed pressure areas on the percussive member.
7. In valve mechanism for fluid pressure percussive tools of the type having a cylinder and a percussive member reciprocable therein, in combination, a spool valve having 60 end heads of equal diameter and a reduced connecting portion, means continuously passing motive fluid in limited amount to both ends of the valve, means comprising ports and passages controlled by one of said heads for directing motive fluid in alternation to opposed pressure areas on the percussive member, and the other valve head controlling 65 an exhaust port for one of said areas. 70
8. In valve mechanism for fluid pressure percussive tools of the type having a cylinder and a percussive member reciprocable therein, in combination, a spool valve having 75 end heads of equal diameter and a reduced connecting portion, ports and passages controlled by said valve extending to opposed pressure areas in the percussing member, independent passages extending to the valve chamber for conducting motive 80 fluid thereto, one head of said valve controlling in alternation the admission of motive fluid from said second named passages to said first named passages, one of said motive fluid passages being independent of 85 said percussive member and the other motive fluid passage being controlled by said percussive member. 90
9. In valve mechanism for fluid pressure percussive tools of the type having a cylinder and a percussive member reciprocable 95 therein, in combination, a spool valve having end heads of equal diameter and a reduced connecting portion, ports and passages controlled by said valve extending to opposed pressure areas of the precussing member, separate passages extending to the valve chamber for conducting motive fluid thereto, one head of said valve controlling 100 in alternation the admission of motive fluid from said second named passages to said first named passages, one of said motive fluid passages being independent of said percussive member and the other motive fluid passage being controlled by said percussive member. 105
10. In combination in a fluid pressure percussive tool having a cylinder with a two diameter bore, a two diameter hammer piston fitting said cylinder bore, said piston having two pressure areas for driving it in one direction and a single pressure area for returning it, one of said first named areas being continuously subjected to motive fluid and the remaining areas being intermittent- 110

ly subjected to motive fluid, a motive fluid supply passage extending to each of said intermittent areas, one of said motive fluid passages being controlled by said piston and the other independent of piston control, and an automatically thrown valve for controlling both said motive fluid supply passages.

11. In combination in a fluid pressure percussive tool having a cylinder with a two diameter bore, a two diameter hammer piston fitting said cylinder bore, said piston having two pressure areas for driving it in one direction and a single pressure area for returning it, one of said first named areas being continuously subjected to motive fluid and the remaining areas being intermittently subjected to motive fluid, motive fluid supply passages extending to said intermittent areas, one of said passages being controlled by said piston and the other independent of piston control, a valve controlling both said passages, and means intermediate said piston controlled passages and the large bore of said piston for preventing leakage of motive fluid from said constant pressure area to one of said intermittent areas.

Signed by me at Detroit, Mich., this 23rd day of January, 1925.
